UNITED STATES PATENT OFFICE.

DANIEL W. ROBERTS, OF CLEVELAND, OHIO, ASSIGNOR TO NATHANIEL D. CHAPIN, TRUSTEE, OF CLEVELAND, OHIO.

FASTENER FOR CAN-COVERS.

No. 796,015.

Specification of Letters Patent.

Patented Aug. 1, 1905.

Application filed July 18, 1904. Serial No. 216,928.

To all whom it may concern:

Be it known that I, DANIEL W. ROBERTS, a citizen of the United States, and a resident of Cleveland, county of Cuyahoga, and State of Ohio, have invented a new and useful Improvement in Fasteners for Can-Covers, of which the following is a specification, the principle of the invention being herein explained and the best mode in which I have contemplated applying that principle, so as to distinguish it from other inventions.

My invention relates to fasteners for can-covers, and particularly to such fasteners as are adapted to temporarily bind the covers tightly to the can.

Said invention consists of means hereinafter fully described, and specifically set forth in the claims.

The annexed drawings and the following description set forth in detail certain mechanism embodying the invention, such disclosed means constituting but one of various mechanical forms in which the principle of the invention may be used.

In said annexed drawings, Figure 1 represents a broken vertical sectional view of a can and my invention applied thereto, the can-cover and fastening member being shown detached. Fig. 2 represents a plan view of a can-cover and the fastening member, the latter being shown in two positions, one of said positions being illustrated in dotted lines.

My invention is adapted to be applied to cans or other receptacles for paints or similar liquid products, and comprises, in combination with the can A, a cover B, which is designed to be fitted within a marginal offset *a*, provided at the top of the can, the cover B being provided with a peripheral flange *b*, bent outwardly at the top, as shown at *b'*, Fig. 1, for the purpose of engaging the offset *a*. An annular independent member C is designed to hold the cover B tightly in contact with the can A, as will now be fully described. This member C is made of spring-steel or other material which will spring under considerable pressure and is broken, as shown in Fig. 2, one of the ends, *c'*, normally bending in and slightly over the other end, *c*, so that when the member C is not pressed out into perfect circular form, as shown in dotted lines in said Fig. 2, the diameter of said member is slightly decreased, thereby enabling the easy insertion of the member within the can-cover. Now if the member be sprung out into

perfect annular form it is adapted by virtue of the length in which it is made to exert considerable pressure upon the flange *b* of the cover B and to press the same tightly up against the can A. To effect this straightening out of the element or member C or its relaxation, as is desired, easily and efficiently, I have provided a lever D, substantially of the construction shown in Fig. 2. This lever is provided with an eccentric rounded head *d*, adapted to fit within and snugly engage the end *c* of the member C, which end is depressed for this purpose, as shown, and an offset *d'*, adapted to lie flush with the end *c'* when the element C is lying in its closed position, as shown in full lines, Fig. 2. The lever D may easily be inserted in the end *c* and against the under side of the end *c'*, as shown in dotted lines in Fig. 2, and then by depressing the same down against the member C, as shown in full lines in said figure, the element C may be straightened out into perfectly circular form and held with considerable pressure against the cover B, the latter, consequently, tightly binding the can A.

It will be noted that the construction provided affords ready means of sealing the can efficiently whenever desired and that such seal may be broken without destroying or injuring any parts of the fastener by merely raising the lever D and allowing the end *c'* of the member C to spring inwardly into its normal position, as shown in dotted lines in Fig. 2. The device is, therefore, especially adapted for use upon those cans to whose contents it is desired to obtain access often, and the sealing of which, nevertheless, should be very perfect when they are closed.

Other modes of applying the principle of my invention may be employed instead of the one explained, change being made as regards the means herein disclosed, provided the means stated by any one of the following claims or the equivalent of such stated means be employed.

I therefore particularly point out and distinctly claim as my invention—

1. The combination with a can-cover; of an annular member adapted to lie within such cover contiguous to the periphery thereof; and an independent member adapted to engage said annular member and spring the same out against the cover to bind the latter tightly to the can.

2. The combination with a can-cover; of a

broken annular member adapted to lie within such cover contiguous to the periphery thereof; and an independent member adapted to engage the ends of said annular member and spring the latter out against the cover to bind the same tightly to the can.

3. The combination with a can-cover; of a broken annular member, one of whose ends is normally out of contact with said cover; and independent means adapted to engage both ends of said member and spring the latter out against the cover to bind the same tightly to the can.

4. The combination with a can-cover; of

an independent broken annular member provided with a depressed end and adapted to lie within said cover contiguous to the periphery thereof; and a lever provided with a head constructed to fit said depressed member end and to bear up against the other end of said member, whereby the latter may be sprung out against the cover to bind the latter tightly upon the can.

Signed by me this 15th day of July, 1904.

DANIEL W. ROBERTS.
